UNITED STATES PATENT OFFICE.

JAMES A. WALKER, OF ROCKFORD, ILLINOIS.

BOW-FACING SELF-FEATHERING PADDLE FOR BOATS.

SPECIFICATION forming part of Letters Patent No. 638,081, dated November 28, 1899.

Application filed August 15, 1898. Serial No. 688,657. (No model.)

To all whom it may concern:

Be it known that I, JAMES A. WALKER, a citizen of the United States, residing at Rockford, in the county of Winnebago and State 5 of Illinois, have invented certain new and useful Improvements in Bow-Facing Self-Feathering Paddles for Boats, of which the following is a specification.

The object of this invention is the production of a simple and efficient means for the 10 propulsion of boats.

In the accompanying drawings, Figure 1 is a front elevation of the rowing mechanism for one side of a boat constructed as contemplated by my invention. Fig. 2 is a side elevation of the same, showing the paddle turning to enter the water for the stroke and in dotted lines illustrating the position of the paddle as it returns edgewise through the 15 water. Fig. 3 is an enlarged plan view of the main bearing of the apparatus, broken away to show the interior arrangement of the parts thereof. Fig. 4 is a face view of the governing-segment, the peculiar conformation of the periphery of which turns the paddle for feathering. Fig. 5 is a perspective view 20 of the sleeve which surrounds the arm of the paddle.

Like letters of reference indicate corresponding parts throughout the several views.

A is the propelling-paddle.

A' is the arm or handle thereof.

A² is a sleeve for surrounding the handle of the paddle A.

35 A³ is a circular collar secured to the sleeve A² at its upper end.

A⁴ is a rectangular collar fixed on the lower end of the sleeve A².

40 A⁵ is an eccentric clamp for securing the handle A' of the paddle A within the sleeve A².

B is an oscillatory bracket for surrounding the sleeve A², within which bracket the sleeve is journaled. The collars A³ and A⁴ hold the sleeve A² within the bracket B.

45 B' is a horizontally-extending shaft, upon the end of which the bracket B is fixed. B² is a hand-lever having a connection with the opposite end of the shaft B'.

50 B³ is a thumb-screw which permits an adjustment of the hand-lever B² with reference to the length of the lever.

B⁴ is an enlarged portion of the shaft B'.

C is the supporting journal-box for the shaft B', so arranged as to permit an endwise movement of the said shaft with reference to the 55 box.

C' is a spiral spring coiled around the shaft B' and lying between a portion of the journal-box C and the shoulder formed by the enlarged portion B⁴ of the shaft B'. This arrangement of the spring C' permits an outward movement of the shaft B' with relation to the box C against the tension of the spring C'.

D is the governing-segment for feathering 65 the oar. Its curving peripheral surface is traversed by the rectangular collar A⁴ as the paddle A is moved backward and forward. D' and D² are notches or depressions in the said surface, into one of which depressions 70 an angle of the collar A⁴ is drawn by the spring C' at each extremity of the paddle movement and by means of which engagement the sleeve A² is turned a quarter of a revolution in the oscillating bracket B. The 75 paddle A being secured in the sleeve A² of course is turned with it. By means of this engagement and the consequent quarter-turn of the paddle A at each stroke thereof the paddle is caused to "feather" on the return 80 stroke, being quarter-turned at the end of the return stroke, so that it is flat against the water on a direct stroke.

D³ are antifriction - rollers projecting 85 slightly above the surface of the governing- segment D and are intended to be engaged by the rectangular collar A⁴.

E is a supporting-frame for the mechanism, secured by bolts to the seat-board E'. The seat-board E' may be put into any boat, being held in position therein by the action of the turn-button E², engaging the usual seat-rests E³ in boats.

In operation one of the rowing-heads just described is secured in either side of a boat, 95 the oarsman taking his position between them, facing the bow of the boat and grasping the hand-levers B². The handles of these levers are set at a slight angle with and a little in advance of the paddles for greater ease of movement and better position. A backward and forward movement of the handles produces a corresponding movement of the paddles.

Should it become desirable to reverse the

action of the paddles or either of them upon the water, as in backing the boat or in turning it, the paddle may be turned half-way around by throwing it twice to the extremity of the 5 stroke before taking a complete stroke instead of only once to produce a quarter-turn of the paddle for feathering.

I claim—

1. In a self-feathering paddle, in combination, a paddle-blade, a handle therefor, a sleeve fixed on the handle which sleeve has a rectangular collar, an oscillatory shaft, a lever for actuating the shaft and a governing-segment having two indentations in its peripheral surface for engaging the rectangular collar of the sleeve and turning the paddle for feathering, substantially as and for the purpose specified.
2. In a self-feathering paddle, in combination, a paddle-blade, a handle therefor, a sleeve on the handle, which sleeve has a rectangular collar, an oscillatory shaft for sup-

porting the paddle, which shaft is capable of an endwise movement, a spring for the shaft, a governing-segment having an irregular peripheral surface for engaging the rectangular collar and turning the paddle for feathering, substantially as and for the purpose specified.

3. In a self-feathering paddle, in combination, a paddle-blade, a handle therefor, a sleeve having a rectangular collar, an eccentric clamp for securing the sleeve to the handle, an oscillatory shaft, a bracket fixed to the shaft surrounding the sleeve, a lever for actuating the shaft, and a governing-segment 35 having an irregular peripheral surface for engaging the rectangular collar and turning the paddle for feathering also having two anti-friction-rollers in said surface, substantially as and for the purpose specified.

JAMES A. WALKER.
